(57) CLAIM

The ornamental design for a hair removal device, as shown and described.

DESCRIPTION

FIG. 1 is a bottom view of a hair removal device, showing my new design;

FIG. 2 is a side view thereof;

FIG. 3 is a top view thereof;

FIG. 4 is a front view thereof;

FIG. 5 is a rear view thereof;

FIG. 6 is a front perspective view thereof;

FIG. 7 is a rear perspective view thereof; and,

FIG. 8 is a bottom perspective view thereof.

The broken lines illustrate portions of the hair removal device and form no part of the claimed design.

The nature and intended use of the article in which the design is embodied is that of a light energy device for hair removal.
